CLAIM

The ornamental design for a misting and sipping bottle cap, as shown and described.

DESCRIPTION

FIG. 1 is a front perspective view of a misting and sipping bottle cap showing our new design;

FIG. 2 is a rear perspective view thereof;

FIG. 3 is a right side elevational view thereof;

FIG. 4 is a left side elevational view thereof;

FIG. 5 is a rear elevational view thereof;

FIG. 6 is a front elevational view thereof;

FIG. 7 is a top plan view thereof; and,

FIG. 8 is a bottom plan view thereof.

The broken lines immediately adjacent to the shaded areas of the misting and sipping bottle cap define the boundaries of the portions of the article not claimed, and form no part of the claimed design. All other broken lines are environment and form no part of the claimed design.

1 Claim, 8 Drawing Sheets
